UNITED STATES PATENT OFFICE.

JOHN CRAWFORD, OF BROOKLYN, N. Y., ASSIGNOR TO WILLIAM H. WARBURTON, OF NEW YORK, AND THOMAS F. BOYLE AND DANIEL BOYLE, OF BROOKLYN, N. Y.

FIRE-ESCAPE.

SPECIFICATION forming part of Letters Patent No. 274,278, dated March 20, 1883.

Application filed June 15, 1882. (No model.)

To all whom it may concern:

Be it known that I, JOHN CRAWFORD, of the city of Brooklyn, in the county of Kings and State of New York, have invented a certain new and useful Improvement in Fire-Escapes, of which the following is a specification.

My invention relates to that class of fire-escape which consists of a folding ladder, one upright of which is secured to the exterior of the building, while the other upright is adapted to swing downward and away from the fixed upright to open the ladder, the rounds or rungs being pivoted to both uprights, and to be operated or moved in a reverse direction for closing the ladder.

The invention consists in the combination, with the folding ladder, of novel means for retaining it folded and for supporting the movable upright when the ladder is opened, and in details of construction hereinafter described and claimed.

In the accompanying drawings, Figure 1 represents an elevation of a building and two fire-escapes secured thereto, and both embodying my invention and both being represented as closed. Fig. 2 represents a vertical section of the front of the wall of the building and one of the fire-escapes opened or let down ready for use. Fig. 3 represents a horizontal section on the dotted line xx , Fig. 1, showing the ladder opened. Fig. 4 represents a similar section on the dotted line yy , Fig. 1. Fig. 5 represents a vertical section of a portion of the wall and the other fire-escape, showing the ladder ready for use. Fig. 6 represents a sectional view of a support for the ladder when open, and which is also shown in Fig. 5. Fig. 7 represents a sectional view, upon a larger scale, showing the construction of the ladder. Fig. 8 represents a section on the dotted line zz , Fig. 7; and Fig. 9 is a detail view, hereinafter described.

Similar letters of reference designate corresponding parts in all the figures.

I will first describe the manner in which I prefer to construct the folding ladder which I make use of; but I do not confine myself to the particular construction, as it can be made in other ways than as here shown. The con-

struction of the ladder is best shown in Figs. 2, 5, 7, and 8.

A designates the fixed upright, which consists simply of a flat plate adapted to be secured to the wall B by bolts or otherwise, and A' designates the movable upright, which consists of a channel-iron of proper size.

C designates the rounds or rungs, which consist of iron bars pivoted at one end to fulcrum-pieces a, riveted to the fixed upright A, and at the other end to fulcrum-pieces b, riveted to the movable upright A'. Each of the fulcrum-pieces a b is formed with ears or lugs, between which the rounds or rungs C fit, and to which they are pivoted. In order to aid in preventing the movable upright from dropping, so as to carry the rungs C beyond a horizontal position, I form the fulcrum-pieces a so that they afford a bearing, a', for the rungs when in a horizontal position, and I give the rungs an angular formation at the outer end, b', so that they abut against the fulcrum-pieces b when in a horizontal position. When the ladder is folded up, as shown in dotted lines in Fig. 7, the rungs C are received in the channel-iron upright and protected from the weather, so that the joints are not liable to rust, and so that the rungs cannot become covered with ice, and thus render it unsafe for persons descending thereon.

Referring now to the ladder shown at the right hand of Fig. 1, and also in Figs. 2, 3, and 4, D designates platforms which are hinged to the wall B at c, so that they may swing up close against the wall, as shown in Fig. 1, or outward and downward, as shown in Figs. 2 and 3, so as to afford a resting-place for persons in passing from the windows of the building to the ladder. These platforms D are provided with openings for the ladder, which are large enough to permit persons to pass down through the platforms on either side of the ladder, and each platform comprises a rod or brace, D', which is inserted through the movable upright A', and is offset at d, on each side thereof, so as to brace and stay the ladder laterally. The platform D may have either a curved or angular profile, both forms being shown in Fig. 1. Near the lower end of the ladder the movable upright A' is braced and stayed laterally by

yokes or stirrups E, which are hinged at e to the wall B, and are pivoted to the upright A'; and the ladder and the lower yoke or stirrup, E, are adapted to swing upward between lugs 5 or brackets f, through which a pin or bolt, g, may be inserted to retain the ladder in a folded position. The pin or bolt g may be constructed so that it may be locked to prevent its withdrawal by any person who has not a proper 10 key, and by this means I prevent any burglar from opening the ladder to enable him to ascend thereon. I may also attach a bell, F, by a chain or connection, h, to the movable upright A', so that it will be rung when the ladder is opened; and I may carry a system of bell-wires through the building and connect them, so that several bells will be rung by the 15 unlocking and opening of the ladder.

In case of fire this ladder will also serve as 20 a means of ascent for the firemen, to enable them to carry hose into the burning building without the necessity of stopping to raise ladders; and this ladder affords a far more stable and effective support than any ladder loosely 25 placed against the wall of the building.

In case of very high buildings the ladder would require considerable power to raise and close it, and to enable this to be done readily I may provide a hand-lever, G, which may be 30 applied to the lower stirrup or yoke, E, as clearly shown in Fig. 2.

Referring now to the ladder represented at the left in Fig. 1, it will be seen that this ladder does not extend clear to the ground, but 35 ends above the first story, and is therefore suitable for a store. In order to support the movable upright A' when the ladder is open, I provide a bracket, H, bolted or otherwise securely fastened to the wall B, and having a 40 cavity, recess, or socket in which the lower end of the upright A' is received when the ladder is opened for use, and by which the said upright is held against lateral movement.

This ladder, like the one before described, 45 is intended to fall by its own weight when released, and to retain it in its closed position I may employ any suitable devices.

I have here represented a rod, I, extending down on the front of the wall B and connected 50 with the movable upright A' by a chain or other connection, i, which passes over a pulley, j, as clearly shown in Fig. 1. This rod I is adapted to slide vertically, and also turn in bearings k, and adjacent to the sill of each 55 window-opening it has secured on it a handle, l. When the ladder is raised or closed the handles l may be turned under catches m,

through which the rod passes, and which are open on one side, as shown best in Fig. 9, and the said handles form stops for engaging with 60 the catches.

When the ladder is to be dropped or opened a person leaning from any window adjacent to which the rod I passes can turn the rod by one of the handles l, so that all the handles 65 will come opposite the open sides of the catches m, and the rod then rises and the ladder opens by the weight of its movable upright.

Near the upper end of each ladder is a yoke, 70 J, fixed to the wall B, and holding the ladder against lateral movement or swinging side-wise, and the step or bracket H also serves a like purpose in the case of the ladder last described.

By my invention I provide a fire-escape 75 which, when folded up, will detract little from the appearance of a building, which is very strong, and upon which any number of persons may descend at once and with safety.

I do not claim, broadly, a folding fire-escape 80 ladder composed of a fixed upright, a movable upright, and rungs pivoted in both said uprights, one or both of the uprights being recessed on their inner or adjacent sides to receive the rungs when the movable upright is 85 swung upward against the fixed upright, and also being provided with integral shoulders, against which the rungs bear when the ladder is open, and which tend to prevent the movement of the rungs below a horizontal position. 90 I am aware that fire-escape ladders of this construction have been before made.

What I claim as my invention, and desire to secure by Letters Patent, is—

1. The combination, with a building, of the 95 folding ladder, one upright of which is secured to the exterior of the building, and the other of which is movable downward and outward from the building, the rod connected with the movable upright by a chain or other connection, 100 the stationary catches on the building, and stops on the rod, adapted to engage with said catches to hold the ladder closed, substantially as described.

2. The combination of the fixed plate or upright A and its attached fulcrum-pieces a, provided with bearings a', the movable channel-upright A' and its attached fulcrum-pieces b, and the pivoted rungs C, having the angular formation b', substantially as described. 115

JOHN CRAWFORD.
